UNITED STATES PATENT OFFICE.

CHARLES STREB, OF ROCHESTER, NEW YORK, ASSIGNOR OF ONE-HALF TO FITZ HENRY BOYER, OF ROCHESTER, NEW YORK.

FOOTWEAR.

1,205,579.

Specification of Letters Patent. Patented Nov. 21, 1916.

Application filed January 22, 1912, Serial No. 672,575. Renewed August 11, 1916. Serial No. 114,467.

To all whom it may concern:

Be it known that I, CHARLES STREB, of Rochester, in the county of Monroe and State of New York, have invented a new and useful Improvement in Footwear, which improvement is fully set forth in the following specification and shown in the accompanying drawings.

The present invention relates to foot-wear and more particularly to the type having metal soles so formed that moisture is excluded from the interior of the foot-wear, and an object of this invention is to provide a construction in which the upper is so connected to the sole that the seam between the said parts sheds water.

Another object of the invention is to provide a heel which is formed separately from the main sole of foot-wear of this type in order that internal fillers may be dispensed with and the wear on the sheet metal sole reduced to a minimum, thus prolonging the life of the foot-wear.

Still another object of the invention is to provide foot-wear of this type with a removable sole to the end that one set of tools may be employed for making the foot-wear, while each individual may have soles which will correspond to his needs, some requiring rubber or leather soles, others requiring calked soles, and still others plain metal soles.

To these and other ends the invention consists in certain parts and combination of parts all of which will be hereinafter described, the novel features being pointed out in the appended claims.

In the drawings: Figure 1 is a side view of a shoe constructed in accordance with this invention; Fig. 2 is a bottom view of the shoe; Fig. 3 is a section on the line *a—a* Fig. 2; Fig. 4 is a detail perspective view of the heel; Fig. 5 is a detail view of the main sole with the supplemental sole and heel removed; and Fig. 6 is a detail view showing the calked supplemental sole.

In carrying out this invention, there is provided an upper 1 of any suitable construction, and a main sole which preferably is made of sheet metal such as aluminum, being provided with the surrounding upturned flange 3. The upper is preferably connected to the exterior of this flange so that such upper projects beyond the flange 45 and in this way sheds water or other liquid

falling on the foot-wear. In this instance, the connection between the flange is formed by bending the upper edge of the flange outwardly and downwardly as at 4 and turning the lower edge of the upper inwardly and upwardly, as shown at 5, the upwardly extending portion being clamped or held by the downwardly turned portion 4 in the manner shown in Fig. 3.

The rear portion of the sole 2 is preferably arranged in a higher plane than the forward portion and is supported in this elevated position by a heel which is formed separately from the main sole. This heel may be detachable in order that it may be replaced, when worn out, by a new one or have a heel of another type substituted therefor. In the present embodiment, to secure the heel in place, the main sole 2 is provided at the base of its flange 3 with a guide in the form of a rib 6 which extends around the rear end of the sole and along opposite sides thereof, this rib being preferably formed by pressing outwardly the metal of the flange 3. Coöperating with the rib 6 is a guide on the heel comprising, in this instance, a grooved flange 7 formed by turning all of the edges of the plate 8 upwardly except the forward edge. The plate 8 is also formed of sheet material, preferably aluminum and is secured to the top of the heel 9 in any suitable manner.

It is apparent that the heel 9 may be made of leather, rubber or metal to correspond with the requirements of the user of the foot-wear. The heel is fitted to the main sole by a forward sliding movement and is held in position in any suitable manner but preferably connected with the removable supplemental sole as will be hereinafter described.

The under side of the main sole, near the forward end thereof, is curved on an arc which facilitates the attachment and detachment of a supplemental sole. The features of construction of the detachable heel are also embodied in this sole. The flange 3 is provided at its base with a rib 10 struck up from the metal of the flange, said rib extending around the front end of the sole and also along the sides thereof substantially to the middle of the foot-wear. Those portions of the rib or guide 10 arranged along the sides of the foot-wear are struck on an arc which has a common center with the 110

- curve of the under side of the main sole so as to be concentric with said sole curve. This arrangement, of course, facilitates the removal and the attachment of the supplemental sole. The supplemental sole may also be formed of a sheet of metal, such as aluminum, which has its front and side edges turned upwardly to provide a grooved guide 12 for coöperation with the guide 10. 5
- 10 To the under side of this attaching member, a wearing member 13 is secured and may be in the form of leather, rubber, metal or other suitable material, being in this instance in the form of leather stitched to the attaching 15 plate 11 as at 14.
- For holding the supplemental sole and the heel upon the main sole 2, the supplemental sole may be provided with a rearward extension 15 and the heel may be provided 20 with a forward extension 16. These extensions are connected, the former being provided with a slot 17 and the latter having a pivoted turning latch 18 adapted to be passed through the slot and turned to hold 25 the parts together. As the supplemental sole and the heel connect with the main sole by sliding movements in opposite directions, they are, by reason of the connection uniting them, held against accidental removal 30 from the main sole. As shown in Fig. 6, the sheet metal plates 8 or 11 may carry wearing portions in the form of studs or calks 19.
- To protect the foot of the wearer against 35 contact with the upturned flange of the main sole, there may be provided a covering in the form of felt or cloth 20, the latter being secured in place by a thin piece of sheet material which extends into the seam as 40 shown in Fig. 3, and passes above the upper edge of the flange 3. An inner sole 22 of felt or other suitable material may be employed for protecting the foot against the metallic insole 2.
- 45 Foot-wear of this type can be employed in any place where there is an excess of water or moisture. It is particularly advantageous for farmers and in establishments such as ice cream plants, tanning factories and other places where water or other liquids are extensively used. The main sole is seamless and is not perforated for the attachment thereto of calks or other wearing 50 portions. The foot-wear will last longer because of its seamless structure and the fact that the sole and heel may be detached when worn out. The seam between the main sole and the upper is such that it is both inexpensive to form and, at the same time, it 55 sheds water or other liquids. The inner covering or lining is attached in such a man-

ner that separate operations in securing the same are not required, one seam connecting the covering, the upper and the flange of the main sole.

65

What I claim as my invention and desire to secure by Letters Patent is:

1. Foot-wear comprising an upper made of flexible material, and a sole of metal having a surrounding upturned flange secured to the upper, the upturned flange of said sole being bent to provide guides at its front and its rear end to be engaged by a detachable sole and a detachable heel respectively. 70
2. Foot-wear comprising an upper, and a sole of sheet metal having a surrounding upturned flange secured to the upper, said upturned flange being bent to provide a guide for engagement by a detachable sole. 75
3. Foot-wear comprising an upper, a main sole of sheet metal having an upwardly turned flange, the under side of the rear portion of the sole being in a higher plane than the forward portion and the flange having a rib bent from the same at the rear thereof, 80 and a heel formed separately from the sole and engaging the rib of the flange to be held to the sole. 85
4. Foot-wear comprising an upper, a main sole of sheet metal having a surrounding upturned flange, the rear portion of said sole being in a higher plane than the forward portion and bent above its lower surface to provide guides, and a heel having guiding portions coöperating with the guides on the 90 main sole. 95
5. Foot-wear comprising an upper formed of flexible material, and a sole of metal having a surrounding upturned flange with a rib extending around the front end thereof 100 and along opposite sides of the same, the bottom of the sole being curved on an arc, and the ends of the rib lying at the sides of the sole being also curved on an arc which is concentric with the curve of the bottom of 105 the sole.
6. A metal sole having a surrounding upwardly-extending flange, the under side of said sole being curved at the forward portion from a point in proximity to the arch 110 of the shoe to the toe thereof and extending in a straight line from said curved portion to the rear end of the shoe, the sole being formed from one piece of sheet metal, and the upper surface of the sole at the heel portion thereof being substantially in a plane with the high point of the arch. 115
